WILHELM C. G. BERNDT, OF KENESAW, NEBRASKA.

BUNDLE-CARRIER ATTACHMENT FOR BINDERS.

1,139,013.

Specification of Letters Patent.

Patented May 11, 1915.

Application filed May 27, 1914. Serial No. 841,318.

To all whom it may concern:

Be it known that I, WILHELM C. G. BERNDT, a citizen of the United States, residing at Kenesaw, in the county of Kenesaw and State of Nebraska, have invented a new and useful Bundle-Carrier Attachment for Binders, of which the following is a specification.

The invention relates to a bundle carrier attachment for binders.

The object of the present invention is to provide a simple, practical, and efficient device designed to be readily applied to various binders and adapted to retain the bundles of grain on a carrier while the machine is traveling from one windrow to another, and capable of preventing the bundles from slipping off the carrier and also from turning and falling through the same, and at the same time, enabling the carrier to hold an increased number of bundles.

A further object of the invention is to provide an attachment of this character capable of being folded compactly against the machine when the bundle carrier is folded, for the purpose of reducing the width of the machine, so that the same may be driven through narrow places.

With these and other objects in view the invention consists in the construction and novel combination of parts hereinafter fully described, illustrated in the accompanying drawings, and pointed out in the claims hereto appended, it being understood that various changes in the form, proportion, size and minor details of construction, within the scope of the claims, may be resorted to without departing from the spirit or sacrificing any of the advantages of the invention.

In the drawings:—Figure 1 is a perspective view of a portion of a binder provided with a bundle carrier attachment constructed in accordance with this invention. Fig. 2 is a plan view of the same. Figs. 3 and 4 are detail sectional views illustrating the construction of the link connection of the top rod. Fig. 5 is a detail sectional view through the bearing bracket, illustrating the manner of mounting the front rod. Fig. 6 is a detail perspective view of the bearing bracket.

Like numerals of reference designate corresponding parts in all the figures of the drawings.

In the accompanying drawings, in which

is illustrated the preferred embodiment of the invention, the bundle carrier attachment comprises in its construction a top rod or member 1 and a front rod or member 2. The top rod or member 1, which extends over the top of the bundle carrier 3 of a binder, is preferably constructed of a single piece of rod metal and consists of a straight inner portion 4, an angularly disposed intermediate portion 5, and a substantially L-shaped outer portion 6. The straight inner portion extends outwardly at a slight inclination from the top portion of the machine to a point above the front portion of the bundle carrier, and the intermediate portion 5, which is also set at an inclination, extends outwardly and rearwardly at a slight angle to the inner portion 4, while the L-shaped outer portion 6 extends downwardly and rearwardly, forming an angularly disposed terminal portion 7. The grain, after being bundled and tied, is deposited upon the bundle carrier 3 in the ordinary manner, and the top rod extends over the bundles and is adapted to engage and prevent the same from slipping off the ends of the rods or tines of the bundle carrier, and the angularly disposed terminal portion 7 also operates to prevent the bundles from turning on the bundle carrier and dropping through the same.

The top rod, which is provided at its front end with an eye 8, is mounted on an upwardly extending pivot 9, preferably carried by an attaching plate 10, which is suitably secured to the top portion of the machine. The eye 8 is retained on the upwardly extending pivot 9 by a key 11 or other suitable fastening means, and the said pivot permits the top rod to be swung rearwardly and inwardly to the dotted line position illustrated in Fig. 2 of the drawings when the bundle carrier is folded to reduce the width of the machine. The top rod, which is resilient, is connected at an intermediate point with the machine by a link 12, provided at one end with an eye 13 and having an open bearing 14 at its other end, consisting of a slot and receiving the inner straight portion of the top rod, which is detachably confined in the bearing slot by a key 15. The key 15, which extends across the slot, as clearly illustrated in Fig. 3 of the drawings, is mounted in a suitable perforation or bore and is adapted to be withdrawn therefrom when it is desired to dis-

connect the top rod from the link, for the purpose of permitting the rod to be swung rearwardly to its folded position. The resiliency of the top rod and the intermediate 5 link connection enables the top rod to yield as the bundles accumulate on the bundle carrier, which is adapted to hold an increased number of bundles, it being found by experience that the bundle carrier of an 10 ordinary binder equipped with the present device is adapted to carry with safety from six to twelve bundles more than it is possible for it to carry without the attachment. The eye 13 is pivoted by an approximately 15 horizontal bolt 16 to an ear 17 of a bearing plate 18, bolted or otherwise secured to the machine at a convenient portion thereof. The link is adapted to swing upwardly from an approximately horizontal position to a 20 vertical position, and the outer portion of the rod is also capable of being flexed or bent slightly to adjust itself to the increasing size of the contents of the bundle carrier as the bundles are deposited thereon. 25 When the bundle carrier is operated in the usual manner to discharge the bundles, the top rod automatically regains its normal position. The open bearing slot and the removable key enable the top rod to be easily 30 and quickly connected with and disconnected from the pivoted link 12.

The front rod 2, which is approximately L-shaped, consists of a front portion 19 and a side portion 20. The front portion 19 extends across the front of the bundle carrier at a point above and slightly in advance of the same in substantial parallelism with the vertical planes of the rods of the said carrier, and the side portion 20 which extends rearwardly along the outer portion of the bundle carrier intersects the vertical planes of the rods of the latter; and is adapted to be flexed or bent outwardly slightly as the bundles accumulate on the carrier. The front 40 rod, which prevents the bundles from falling over the front of the carrier, is adapted to automatically regain its normal position when the bundles are discharged from the carrier. The terminal 21 of the side portion 45 20 is bent outwardly slightly to prevent it from being caught in a bundle. The device is adapted to be applied to various styles and sizes of binders, and the top and front rods may be varied in size and configuration 50 to adapt the attachment to various styles, sizes, and kinds of binders. The front rod is provided at its inner end with a vertical pivot 22, mounted in alined openings of spaced upper and lower ears or lugs 23 of 55 a bearing bracket 24. The pivot, which extends downwardly from the front portion 19 of the front rod, is provided in its lower end with a perforation 25 for the reception of a key 26, which retains the pivot in the 60 bearing openings of the projecting ears or 65

lugs 23 of the bearing bracket. The bearing bracket 24, which is bolted or otherwise secured to one of the bars or members of the machine, is provided with a recess 27 for the reception of such bar or member. The 70 bearing bracket, which has an enlarged top portion 28, is provided with a recess 29 opening rearwardly and receiving the front portion 19 of the front rod 2, which is detachably confined in the recess 29 by a key 75 30 extending across said recess 29 and mounted in alined perforations 31 of the upper and lower walls thereof. The key 30 is adapted to be removed to permit the front rod or member 2 to swing rearwardly 80 and inwardly to the folded dotted line position shown in Fig. 2 of the drawings.

What is claimed is:—

1. A bundle carrier attachment for binders including a top rod or member provided at 85 its inner end with attaching means and arranged to extend outwardly over the bundle carrier of a binder and downwardly at the outer portion thereof to prevent the bundles from slipping off the bundle carrier at the 90 outer side of the same, said top rod or member being provided with a terminal rearwardly extending portion arranged to prevent the bundles from turning on the bundle carrier and falling through the same. 95

2. A bundle carrier attachment for binders including a top bar or member arranged to extend outwardly over the bundle carrier and downwardly at the outer portion thereof, means for pivoting the inner end of the 100 rod or member, and a pivoted link connected with the rod or member at a point intermediate of the ends thereof and arranged to permit the same to move upwardly a limited distance. 105

3. A bundle carrier attachment for binders including a top bar or member arranged to extend outwardly over the bundle carrier and downwardly at the outer portion thereof, means for pivoting the inner end of the 110 rod or member, and a link pivoted at one end and provided at the other end with an open bearing receiving the top rod or member at a point intermediate of the ends thereof, said link being provided with means for detachably retaining the said rod or member in the bearing, said pivot permitting the rod or member to swing inwardly with respect to the machine. 115

4. The combination with the bundle carrier of a binder, of a bundle carrier attachment including a front rod or member comprising a front portion and an outer rearwardly extending portion, means for movably mounting the inner end of the front 120 portion of the rod on the binder independently of the bundle carrier to permit the front rod or member to fold against the binder, and means also mounted independently of the bundle carrier for detachably 125 130

holding the front rod or member in its operative position.

5. The combination with a binder having a bundle carrier composed of spaced transverse rods, a front rod or member comprising a front portion located above and in substantial parallelism with the vertical planes of the rods at the front of the bundle carrier, said front rod or member being provided at its inner end with attaching means and having a rearwardly extending portion intersecting the vertical planes of the rods of the bundle carrier and arranged to be flexed by bundles accumulating on the said carrier.

6. A bundle carrier attachment for binders including a front rod or member arranged to extend across the bundle carrier at the front thereof and provided with an outer rearwardly extending portion, said rod or member being also provided at its inner end with a pivot, and a bearing bracket receiving the pivot and provided with means for detachably engaging the rod beyond the pivot, said means being adapted to retain the rod normally in an operative position and also permitting the rod to swing inwardly and rearwardly to fold it.

7. A bundle carrier attachment for binders including a front rod or member arranged to extend across the front of a bundle carrier and provided at its inner end with a depending pivot, a bearing bracket receiving the pivot and provided at the top with an ap-

proximately horizontal recess through which the rod or member passes, said recess being open at one side to permit the rod or member to swing on its pivot, and means for detachably confining the rod or member in the recess of the bearing bracket.

8. A bundle carrier attachment for binders including a top rod or member arranged to extend outwardly over a bundle carrier and downwardly at the outer portion thereof, and an approximately L-shaped front rod or member arranged to extend across the front of the bundle carrier in advance of the top rod and rearwardly along the outer side thereof to a point in rear of the said top rod.

9. A bundle carrier attachment for binders including a top rod or member arranged to extend outwardly over a bundle carrier and downwardly at the outer portion thereof, an approximately L-shaped front rod or member arranged to extend across the front of the bundle carrier in advance of the top rod and rearwardly along the outer side thereof to a point in rear of the said top rod, and means for mounting the said rods or members to permit the same to fold against a binder.

In testimony, that I claim the foregoing as my own, I have hereto affixed my signature in the presence of two witnesses.
